FLUID DISPENSER

Henry C. Keck and Burnie M. Craig, Pasadena, and
Thomas K. Hale, Glendale, Calif., assignors to Dispensers, Inc., Los Angeles, Calif., a corporation of California

Application January 10, 1958, Serial No. 49,190

Term of patent 14 years

(Cl. D44—21)

Fig. 1 is a perspective view of a fluid dispenser embodying our new design;

Fig. 2 is a top plan view; and

Fig. 3 is a side elevational view thereof.

We claim:

The ornamental design for a fluid dispenser, substantially as shown.
